UNITED STATES PATENT OFFICE

WILLIAM C. CARTER, OF FLINT, MICHIGAN

CARBURETOR

Application filed October 17, 1927. Serial No. 226,684.

This invention relates to carburetor.

One object of the invention is to provide a carburetor that is equipped with an adjustable fuel supplying device for delivering fuel to the main passageway of the carburetor at a point in proximity to the throttle valve when said valve is closed or only partly open.

Another object is to provide a carburetor that is equipped with a choking device of novel construction.

Another object is to provide a carburetor that is equipped with a by-pass around the throttle valve, and also equipped with a choking device which is combined with said by-pass in such a way that said by-pass will automatically come into service while the choking device is moving towards its closed position.

And still another object of the invention is to provide a carburetor which is of such a construction that the act of moving the choking device into its closed or partly closed position automatically increases the idle speed of the engine without affecting the throttle valve or the device that is used to determine the idle position of the throttle valve. Other objects and desirable features of my invention will be hereinafter pointed out.

I have herein illustrated my present invention embodied in a carburetor of the general type illustrated in my pending application for patent Serial No. 206,028, filed July 15, 1927, but I wish it to be understood that my present invention is applicable to various other types and kinds of carburetors.

Figure 1 of the drawings is a top plan view of a carburetor embodying my present invention.

Figure 2 is a vertical sectional view of said carburetor, taken on the line 2—2 of Figure 1.

Figure 3 is a view similar to Figure 2, showing the choking device moved into its partly closed position.

Figure 4 is an enlarged detail view of the means that is used to adjust the fuel tube which constitutes the fuel duct through which fuel is conveyed from the accelerating well to the intake above the throttle valve when the throttle valve is closed or only partly open.

Figure 5 is a detail view, illustrating the means that is used to actuate or adjust the choking device; and

Figure 6 is a detail view, taken on the line 6—6 of Figure 3, illustrating the by-pass around the throttle valve that comes into service when the choking device is moved towards its closed position.

Referring to the drawings which illustrate the preferred form of my invention, A designates the body casting of the carburetor which is provided with a straight, vertically-disposed bore 1 that constitutes the main passageway of the carburetor, 2 designates a throttle valve which is arranged in said main passageway adjacent the upper end of same, 3 designates an air chamber which communicates with the lower end of the main passageway, 4 designates a depending cylindrical portion on the body casting that serves as a guide for an annular float 5 in the bowl 6 that constitutes the float chamber of the carburetor, 7 designates an accelerating well or reservoir in the depending portion 4 on the body casting, inside of which is arranged a vertically-disposed tubular member 8 that projects upwardly towards the main passageway 1 in concentric relation with the same and terminates preferably inside of a Venturi member 9 that is arranged inside of the main passageway 1 below the throttle valve, and 10 designates a vertically-disposed fuel supplying device mounted in the body casting A in such a manner that it forms part of a fuel duct or passageway through which fuel is conveyed from the accelerating well 7 to the main passageway 1 at a point above the throttle valve 2 when said throttle valve is closed or only partly open, and through which fuel is conveyed to a by-pass around the throttle valve when the choking device of the carburetor is in its partly closed position.

The lower portion of the fuel duct just referred to can be formed in various ways without departing from the spirit of my invention. It is herein illustrated as being formed by a vertically-disposed groove or bore 11 in the depending portion 4 of the body casting, arranged with its lower end communicating with the bottom or lower end of the accelerating well 7 and

with its upper end communicating with a fuel duct 12 formed in a lug 13 on the body casting that receives the lower end portion of the adjustable fuel supplying device 10, 5 previously referred to, which is herein represented as consisting of a tube. Communication between the fuel tube 10 and the fuel duct 11 just referred to is established by means of a fuel orifice 14 in a plug 15 that is 10 removably mounted in the body casting A, as shown in Figure 2, it being preferable to construct the carburetor in this manner, so as to permit the use of an orifice 14 of a definite size that forms part of the passageway 15 through which liquid fuel is conveyed from the accelerating well 7 to the main passageway 1 above the throttle valve and which can be cleaned easily in the event it becomes stopped up, simply by removing the plug 15 20 and cleaning the orifice 14 in same. Air is admitted from the air chamber 3 to the lower end of the fuel passageway in the fuel supplying device 10, preferably by an air port 16 that is formed in the lug 13. The upper 25 end portion of the fuel supplying device 10 is so formed that when the throttle valve 2 is closed or only partly open, fuel will pass from the upper end of said device into the main passageway 1 at a point above the throttle valve and air will also enter the fuel passageway of said device 10 from the main passageway 1 at a point below the throttle valve, and thus cut down or reduce the suction that is exerted on the upper end of said device 10 35 by the high vacuum which then exists in the intake of the engine. When the throttle valve is moved forwardly away from its idle position the admission of air to the upper end of the fuel passageway of the device 10 is cut off, thereby causing the full force of the vacuum which then exists in the intake of the engine to be exerted on a fuel discharge port or equivalent means located at the upper end of the tube or device 10. In the carburetor herein illustrated the fuel tube 10 is closed at its upper end and is provided at a point below said closed upper end with a lateral fuel discharge port 10a arranged so that when the throttle valve is in its closed position, as 45 shown in Figures 1, 2 and 3, said discharge port 10a will be positioned in close proximity to the throttle valve, usually with the top half of said port projecting above the throttle valve. At a point below said lateral fuel discharge port 10a are one or more air-inlet ports 10b which are located below the throttle valve when said valve is in its closed position.

The means that is used to admit fuel from the float chamber to the accelerating well 7 50 can be constructed in various ways without departing from the spirit of my invention. In the carburetor herein illustrated an orifice 17 of a definite size is provided for admitting fuel from the float chamber to a relatively shallow chamber 7a that is in direct

communication with the accelerating well 7 and which virtually forms the bottom or lower end portion of said accelerating well, communication being established between the accelerating well 7 and the shallow chamber 7a by an orifice 18. The lower end of the fuel duct 11, previously referred to, communicates with the chamber 7a, as shown in Figure 2, and as said chamber 7a is relatively shallow, surging of the liquid fuel away from the liquid end of the fuel duct 11 is effectively prevented at times when the accelerating reservoir contains only a small quantity of fuel. The tubular member 8, previously referred to, that projects upwardly through the accelerating well 7 is provided at its lower end with a main liquid fuel supply device which may either consist of a fuel orifice 19, as shown in Figure 2, or a fuel nozzle that discharges upwardly into the accelerating well. Said tubular member 8 is provided at its lower end with one or a plurality of vertically-disposed slots 20 that project upwardly from the bottom of the accelerating well and which are of such length that their upper ends terminate above the normal level of the fuel in the float bowl, represented by the dot and dash-line in Figure 2.

When the engine is idling with the throttle valve 2 in its closed position, liquid fuel with air will be drawn upwardly through the tube or fuel supplying device 10 and discharged from the upper end of same into the main passageway 1 at a point above the throttle valve, due to the fact that the vacuum in the intake of the engine produces a suction in the fuel passageway of the device 10 that is exerted on the fuel orifice 14 to which liquid fuel is supplied by the duct 11 which leads upwardly from the lower end of the accelerating well, or rather, from the shallow chamber 7a that forms the lower end portion of the accelerating well. Notwithstanding the fact that the lower end of the fuel passageway of the device 10 is in direct communication with a supply of liquid fuel when the throttle valve 2 is in its idle position, only a relatively slight suction exists in the fuel passageway in the device 10, because air is entering the lower end of said fuel passageway from the air chamber 3 through the air port 16 and air is also entering the upper end portion of the fuel passageway in the device 10 through one or more air inlets 10b in same which at this time are located below the throttle valve. After the throttle valve has been moved into such a position that the air inlets or openings 10b in the upper end portion of the device 10 will be positioned above the throttle valve, the high vacuum which exists in the intake of the engine when the throttle valve is partly open will become operative for drawing the fuel upwardly through the fuel passage-

way of the device 10, thus increasing the amount of fuel which said device introduces into the passageway 1. After the throttle valve has reached such a position that the device 10 ceases to supply fuel to the main passageway 1 the air that is drawn upwardly into said passageway through the annular opening between the upper end of the tubular member 8 and the contracted portion of the Venturi member 9 creates a suction inside of the tubular member 8 of sufficient intensity to draw air downwardly through the well 7 and into the vertically-disposed slots 20 in the member 8, and thereafter upwardly through said member 8, thus causing more or less of the fuel in the accelerating well 7 to be absorbed by the air and carried upwardly into the main passageway 1. When the throttle valve reaches such a position as to cause sufficient air to travel through the well 7 to keep said well dry, or practically so, the suction inside of the tubular member 8 becomes strong enough to cause fuel to be drawn from the main liquid fuel supply orifice 19 and carried upwardly through the tubular member 8 into the main passageway 1. Whenever the throttle valve is moved from its high speed position towards its closed or partly open position, the liquid fuel builds up in the accelerating well 7, so as to form an accelerating charge that is in readiness to be carried into the main passageway 1 by the air that rushes downwardly through said well, and thence upwardly through the tubular member 8, if the throttle valve is opened suddenly.

One of the novel features of my present invention consists in constructing the fuel supplying device 10 in such a way that it can be adjusted easily so as to accurately position the fuel discharge orifice 10^a at the upper end of same with relation to the throttle valve 2 when the carburetor is being installed on the engine on which it is used. Various means can be used to adjust the fuel discharge port 10^a of the device 10 with relation to the throttle valve, but I prefer to form the device 10 from a tube mounted in the body casting A of the carburetor in such a way that said tube can be raised or lowered, and provide a means 21 for adjusting said tube vertically, the means 21 herein illustrated consisting of a rotatable plug mounted in the body casting A at one side of the tube 10 and provided at its inner end with an eccentrically-disposed, arc-shaped rib 22, as shown in Figure 4, that enters a notch or groove in one side of the tube 10. The plug 21 is provided in its outer end with a knurled finger piece 23 by which said plug can be rotated, so as to raise or lower the tube 10, and thus accurately adjust the fuel discharge orifice 10^a and the air inlets 10^b at the upper end of said tube with relation to the throttle valve 2, thereby simplifying the manufac-

turing operations and compensating for inaccuracies in machining or assembling. If desired, a means can be used to hold the tube actuating device 21 in adjusted position, such, for example, as a friction element 21^a that acts on some portion of the device 21 or the finger piece of same.

Another novel feature of my present invention consists in arranging a cup-shaped member 24 in opposed relation with the contracted end of the Venturi member 9 and mounting one of said members in such a manner that it can be moved towards and away from the other so as to reduce the admission of air to the main passageway 1 of the carburetor below the throttle valve, thus forming a choking device that is intended to be used to facilitate the starting of the engine when it is cold. Preferably, the Venturi member 9 is reciprocatingly mounted in the body casting A of the carburetor at a point above the cup-shaped member 24 which can be conveniently mounted on the tubular member 8, said cup-shaped member having a rim 24^a against which the lower end of the Venturi member 9 strikes when said Venturi member is moved downwardly into its closed position so as to choke the carburetor. By making the stationary member 24 of the choking device cup-shaped instead of in the form of a continuous flat surface, towards which the movable member 9 of the choking device is moved to choke the carburetor, I am able to materially reduce the stroke or degree of reciprocating movement of said member 9, thereby making the carburetor more compact. In other words, the cavity or depression in the cup-shaped member 24 increases the area of the air passageway through which the air circulates after entering the space between the rim of the cup-shaped member 24 and the lower end of the Venturi member 9 sufficiently to make it practicable to arrange the lower end of the Venturi member comparatively close to the rim 24^a of the cup-shaped member when said Venturi member is in its normal position shown in Figure 2. While I have stated that the abutment member or part 24 that serves as a closure for the lower end of the Venturi member 9, is of cup-shape, I wish it to be understood that the particular form of said abutment member is immaterial, so long as it is provided with a depression or cavity that increases the volume of the passageway through which the air circulates after flowing inwardly between the two opposed members of the choking device. Any suitable means can be used to move the Venturi member 9 towards and away from the cup-shaped member 24, the means herein illustrated for this purpose consisting of a rotatable device 25, mounted in the body casting of the carburetor, and provided at its inner end with an eccentrically-disposed pin or projection 26

that enters a hole in the side of the Venturi member 9. When the device 25 is rotated in one direction, the Venturi member 9 will move downwardly, and when said device is 5 rotated in the opposite direction, the Venturi member will move upwardly. The device 25 is provided at its outer end with a lever 27 for turning the same and a torsion spring 28 is combined with said device 25 10 so as to normally exert pressure on same in a direction to hold the Venturi member, constituting the choking device of the carburetor, in its open or inactive position, as shown in Figure 2.

15 Another novel feature of my present invention consists of a carburetor constructed in such a manner that the act of moving the choking device into its closed or partly closed position automatically increases the 20 idle speed of the engine without affecting the throttle valve or the device that is used to determine the idle position of the throttle valve.

25 In such a carburetor the increased speed of the engine above its normal idle speed, produced by closing the choking device, indicates to the operator in charge of the engine that the choking device should be opened or restored to its normal open position in the 30 event the operator has failed to do this after the engine has warmed up, thereby effectively preventing numerous troubles that result from operating an internal combustion engine with too rich a mixture, as well as tending 35 to conserve on the consumption of fuel.

The above described highly desirable result can be attained in various ways without departing from the spirit of my invention but I prefer to construct the carburetor in 40 such a manner that the act of closing a choking device, of any preferred type, increases the flow or delivery of fuel from a fuel supplying device and also automatically brings into service a throttling by-pass around the 45 throttle valve, which establishes communication between the portions of the main passageway 1, located above and below the throttle valve 2. Likewise, the act of opening said 50 choking device automatically renders inoperative the throttling by-pass above referred to.

The carburetor herein illustrated, which represents the preferred form of my invention, is equipped with a by-pass around the 55 throttle valve that comes into service automatically when the choking device starts to move towards its closed position, and means is provided for automatically increasing the 60 suction on the fuel supplying device 14 when the choking device starts to move towards its closed position. When the choking device is 65 in its fully closed position the by-pass around the throttle valve permits a rich combustible mixture to flow freely into the intake of the 70 engine, and thus facilitates easy starting of 75

the engine when it is cold. Said by-pass also acts as a throttling device in its partly closed position insomuch as it increases the idle setting and makes it possible for the operator in charge of the engine to set the choking device in such a position that the idle speed of the engine will be high enough to eliminate the possibility of the engine stopping if the operator retards the throttle valve when the engine is cold. So far as this feature of my 80 invention is concerned, it is immaterial what type or kind of choking device the carburetor is equipped with; it is immaterial what type or kind of by-pass is used around the throttle valve; and it is immaterial what type or kind of means is used for increasing the supply of fuel when the choking device starts to move towards its closed position.

In the carburetor herein illustrated the throttling by-pass around the throttle valve 85 is formed by two vertically-disposed ducts 29 (see Figure 6) located in the side wall of the main passageway 1 with their upper ends terminating in a notch 30 in said side wall that is in direct communication with the main 90 passageway at a point above the throttle valve 2, and with their lower ends terminating in an arc-shaped groove 31 in said side wall that communicates with said main passageway at a point below the throttle valve. The movable Venturi member 9 that constitutes the choking device of the carburetor is provided in its exterior, adjacent its upper 95 end, with an annular groove 32, and the top edge of said Venturi member is provided with one or more notches 33. Normally, the Venturi member 9 occupies the position shown in Figure 2 of the drawings, in which position the annular groove 32 in the exterior of same is located at a point slightly above the arc-shaped groove 31, previously referred to, that forms the lower end of the by-pass around the throttle valve. At such times there is no communication between the by-pass ducts 29 and the portion of the main passageway 1 below the throttle valve, but there is communication between this portion of the main passageway and the fuel tube 10, which communication is established by an orifice 34 in the side of the fuel tube 10 that registers with the annular groove 32 in the exterior of the 105 Venturi member 9. Accordingly, when the throttle valve is closed, or only partly open, and when the Venturi member 9 is in its raised or normal position, shown in Figure 2, some air will enter the fuel tube 10 from the portion of the main passageway 1 below the throttle valve by passing through the notches 33 downwardly into the annular groove 32 110 in the Venturi member 9, and thence into the fuel tube 10 through the orifice 34 in same, the said air acting to reduce the suction that is exerted in the fuel tube 10 by the intake of the 115 engine.

When the Venturi member 9 that constitutes the choking device of the carburetor is moved downwardly towards its closed position, as shown in Figure 3, the annular groove 32 in the exterior of said member comes into registration with the arc-shaped groove 31, without, however, moving out of registration with the orifice 34 in the fuel supplying device 10, thereby causing the 5 by-pass ducts 29 around the throttle valve to become operative. As soon as said by-pass ducts 29 become operative, the high suction that exists in the intake of the 10 engine is exerted on the orifice 34 in the side of the fuel tube 10, due of course, to the fact that said orifice registers with the 15 annular groove 32 in the exterior of the Venturi member, which, at this time is in communication with the arc-shaped groove 31 20 from which the by-pass ducts 29 lead. Consequently, the suction on the idle speed fuel supplying device 14 will be increased, due to the fact that air ceases to flow into the fuel tube 10 through the orifice 34 in same. The result 25 is that an increased supply of fuel will be drawn upwardly through the fuel tube 10, then laterally through the orifice 34 in same into the annular groove 32 in the exterior of 30 the Venturi member 9, and thence upwardly into the intake of the engine through the by-pass ducts 29 around the throttle valve. By 35 adjusting the Venturi member 9, i. e., moving it towards or away from the stationary element 24 with which it co-operates to form the choking device of the carburetor, the operator 40 can vary the richness of the fuel that is supplied to the intake of the engine when the throttle valve is closed, and accordingly, can 45 vary the idle speed of the engine without changing the position of the throttle valve or the device that is used to control the closed 50 position of the throttle valve.

I, of course, realize that carburetors of conventional design are equipped with choking devices that can be closed or set in a partly closed position, but I believe it is new to equip a carburetor with a choking device, which, when moved towards its closed position, automatically brings into service a by-pass around the throttle valve and changes the volume of the medium flowing through said by-pass according to the position of said choking device. I also believe it is new to construct a carburetor so that fuel will be supplied at a certain approximate rate at idle engine speeds when the choking device of the carburetor is in its wide open position, but the act of moving said choking device towards its closed 55 position automatically increases the rate of flow of fuel being supplied to the main passageway of the carburetor.

Having thus described my invention, what I claim as new and desire to secure by Letters Patent is:

1. A carburetor provided with a main passageway, a throttle valve in said passageway, a fuel supplying device leading from a source of supply of fuel and provided with a fuel discharge opening located in proximity to the edge of said throttle valve for admitting fuel to said main passageway above the throttle valve when said valve is closed or partly open, and means for adjusting said device so as to arrange the fuel discharge opening of same in operative relationship with the throttle valve. 70

2. A carburetor provided with a body portion that has a main passageway, a throttle valve in said passageway, a fuel supplying device mounted in said body portion at one side of said passageway and provided with a fuel discharge opening arranged in proximity to the edge of the throttle valve for admitting fuel to said passageway above the throttle valve when said valve is closed or partly open, and means for shifting said fuel supplying device relatively to said body portion to accurately adjust the fuel discharge opening of same relatively to the throttle valve. 80

3. A carburetor provided with a body portion that has a main passageway, a throttle valve in said passageway a fuel supplying device mounted in said body portion at one side of said passageway and provided with a fuel discharge opening arranged in proximity to the edge of the throttle valve for admitting fuel to said passageway above the throttle valve when said valve is closed or partly open, and a rotatable member in the body portion of the carburetor provided with an eccentrically-disposed part that co-operates with said fuel supplying device to shift said device so as to adjust the fuel discharge opening of same relatively to the throttle valve. 90

4. A carburetor provided with a body portion that has a main passageway, a throttle valve in said passageway, a fuel supplying device mounted in said body portion at one side of said passageway and provided with a fuel discharge opening arranged in proximity to the edge of the throttle valve for admitting fuel to said passageway above the throttle valve when said valve is closed or partly open, and an adjusting member for said supplying device rotatably mounted in the body portion of the carburetor and provided with an eccentrically-disposed part that fits in a notch in the exterior of said device. 100

5. A carburetor provided with a main passageway, a throttle valve in said passageway, a Venturi member mounted in said passageway below said throttle valve and adapted to be adjusted lengthwise of said passageway to arrange it in different positions, a tubular element whose upper end terminates inside of the inlet end of said Venturi member, a stationary cup-shaped member surrounding said tubular element and arranged with its rim 110 115 120 125 130

in opposed relation to the lower end of said Venturi member so as to co-operate with the same to form an air inlet for said passageway, and a manually-operable means for moving 5 said Venturi member relatively to said cup-shaped member.

6. A carburetor provided with a main passageway, a throttle valve in said passageway, an idle speed fuel supplying device which 10 supplies fuel when the throttle valve is in its closed or nearly closed position, a choking device for reducing the admission of air to said passageway, a by-pass around the throttle valve that is rendered operative by the 15 movement of said choking device towards its closed position, and means for automatically increasing the discharge of fuel from said idle speed fuel supplying device when said by-pass comes into service.

20 7. A carburetor provided with a main passageway, a throttle valve in said passageway, a choking device for reducing the admission of air to said passageway, a device that supplies fuel at idle engine speeds, and means 25 whereby the movement of said choking device towards its closed position automatically increases the discharge of fuel from said fuel supplying device and also increases the area of passageway through which the fuel is admitted to the intake of the engine at idle speeds.

8. A carburetor provided with a main passageway, a throttle valve in said passageway, a choking member whose position is adapted 35 to be changed to choke or reduce the admission of air to said main passageway, an idle speed fuel supplying device, a by-pass around the throttle valve, separate and distinct from said idle speed fuel supplying device and 40 adapted to be rendered operative by the movement of said choking member away from its normal open position, and means for causing the discharge of fuel from said idle speed fuel supplying device to increase when said 45 choking member is moved into its closed position and to diminish when said choking member is moved into its open position.

9. A carburetor provided with a main passageway, a throttle valve in said passageway, 50 a fuel duct leading from a supply of fuel for introducing fuel into said main passageway above the throttle valve when said valve is in its closed or nearly closed position, a choking member arranged below the throttle 55 valve for choking or reducing the admission of air to said main passageway, a by-pass around the throttle valve that is rendered operative by the movement of said choking member away from its normal open position, 60 and means for increasing the suction exerted on the source of supply from which said fuel duct leads when said by-pass comes into service.

10. A carburetor provided with a main 65 passageway, a throttle valve in said passage-

way, a fuel duct leading from a supply of fuel for introducing fuel into said passageway above the throttle valve when said valve is in its closed or nearly closed position, a by-pass around the throttle valve, and a choking member reciprocatingly mounted in said main passageway below the throttle valve and arranged so that when it starts to move towards its closed position said by-pass will be rendered operative automatically and a greater suction exerted on the supply of fuel from which said fuel duct leads.

11. A carburetor provided with a main passageway, a throttle valve in said passageway, a fuel duct that leads from a supply of fuel 80 for introducing fuel into said passageway above the throttle valve when said valve is in its closed or nearly closed position, a Venturi member reciprocatingly mounted in said passageway below the throttle valve and 85 adapted to be moved so as to choke or reduce the admission of air to said passageway, a groove in the exterior of said Venturi member that is in communication with the portion of said passageway below the throttle 90 valve, an orifice in said fuel duct that registers with said groove in any position of said Venturi member, and a by-pass around the throttle valve that is brought into communication with said groove as soon as said Venturi member starts to move away from its normal open position.

12. A carburetor provided with a main passageway, a throttle valve in said passageway, a movable Venturi member arranged in 100 said passageway below said throttle valve, a tubular member having its upper end positioned in the contracted portion of said Venturi member, a substantially cup-shaped member surrounding said tubular member 105 and arranged with its open end in opposed relation to the inlet end of said Venturi member so as to co-operate with same to form an inlet opening to said passageway, and means for moving said Venturi member towards and away from said cup-shaped member so as to vary the flow of air upwardly 110 through said Venturi member.

13. A carburetor for an internal combustion engine provided with a main passageway, a throttle valve in said passageway, a choking device for controlling the admission of air to said passageway, said carburetor having means adapted to supply an air and fuel mixture for idling said engine, and means other than the above said means for controlling the idling speed of the engine in addition to the control obtained by the throttle setting, said second means comprising a throttling by-pass around the throttle 115 so arranged that when the choking device is moving towards its closed position said by-pass will automatically come into service.

WILLIAM C. CARTER.
